UNITED STATES PATENT OFFICE.

KIRBY FITZPATRICK, OF OKLAHOMA, OKLAHOMA.

VOTING-MACHINE.

1,171,778.

Specification of Letters Patent. Patented Feb. 15, 1916.

Application filed December 23, 1914. Serial No. 878,766.

To all whom it may concern:

Be it known that I, KIRBY FITZPATRICK, a citizen of the United States of America, residing at Oklahoma city, in the county of 5 Oklahoma and State of Oklahoma, have invented certain new and useful Improvements in Voting-Machines, of which the following is a specification.

This invention relates to a new and useful 10 improvement in voting machines and has for its object the production of a voting machine for preferential voting and in which machine the parts are locked in the act of voting so that one vote only for each 15 candidate may be cast.

The invention consists in a voting machine provided with means for having a vote cast for several candidates of the same party for the same office, the parts being so 20 arranged that one vote only may be cast for each candidate.

In the annexed drawings: Figure 1 represents a view of a portion of a voting machine arranged in two parts for convenience 25 of representation, intervening parts identical in construction with the parts shown being omitted. This figure shows a top view, a view with parts removed, a view with the plate removed and also a transverse section 30 through the sets of tubes. Fig. 2 is a longitudinal section through the machine, parts being omitted. Fig. 3 is an enlarged detail view of part of the operating mechanism. Fig. 4 is an elevation of a portion of the 35 voting tubes.

In these drawings: The numeral 1 represents a portion of a voting machine provided with means for casting votes for candidates of one party. It is to be understood that the device hereinafter described 40 may be made so that it would be adapted either for votes for one party or for several. In the latter case there would be merely a duplication of the construction of the device 45 used for the votes for one party. Also the drawing shows only a portion of the voting machine, parts identical in construction with those shown being omitted. This

machine 1 has the ends 2 and 3, top 4 and bottom 5. The sides are open for ease of 50 inspection. The top 4 has a number of circular holes 6 and the bottom 5 a like number of circular holes 7, the holes 6 and 7 being aligned vertically in pairs and there being enough pairs to adapt the voting machine to the number of offices to be filled. 55 Loose, in each circular top hole 6, is a round spindle 8 of a circular top head 9 within the box 1 under the top 4, the spindle 8 having a threaded bore 10 and projecting 60 upwardly through the circular hole 6. The circular top head 9 is provided with a number of sets of holes a , b , c , etc., consisting of three holes each a^1 , a^2 , a^3 , etc., the holes of 65 each set arranged in triangular form, and like holes of several sets having like location in the head 9. Loose, in each round bottom hole 7, is the enlarged round portion 11 of a spindle 12 of a circular bottom head 13 within the box 1 above the bottom 5, 70 such spindle 12 also having a downwardly extending extension 14.

Extending from the top head 9 to the bottom head 13 are tubes 15, made preferably of glass or having longitudinal slits 75 15¹. These tubes 15 are arranged in sets of three, the upper ends 16 of the tubes 15 being secured in the holes in the top head 9 and the lower ends 17 of the tubes 15 being secured to the bottom plate 13 so 80 that the latter forms the bottom of the tubes 15, and these tubes opening through the head 9 at the holes therein. A screw 18 engages the threaded bore 10 of the spindle 8 and by its head 19 holds upon and above 85 the top 9, a circular plate 20. This plate 20 has a number of sets of holes n , o , p , q , r , etc., consisting of three holes each, n^1 , n^2 , n^3 , etc., the holes of each set arranged in triangular form and like holes of the several 90 sets having like location. The holes in the plate 20 are arranged so as to be in line with the open tops of the tubes 15, as the latter are moved as hereinafter described. At each set of the holes, n , o , p , etc., of the 95 plate 20, there is a disk 21, held by a pivot

22 in the top of the plate 20. Each disk is located so that the pivot 22 comes amidst the holes of each set of holes in the top of the plate 20. Each disk has such diameter 5 that the disk partially covers the top of the holes and the set of holes. There is made in each disk a notch 23 of the same curvature as or similar to that of the holes, *n*, *o*, *p*, etc.

10 Securely fastened upon the extension 14 of the spindle 12, at one end of the machine is a wheel 24, having the teeth 25. Upon the extension 14 of the other spindles 12 are securely fastened crank arms 26. A rod 27 15 connects the several crank arms 26 with the wheel 24. In a slot 28, at the end of the machine, there is loosely held a slide bar 29, having the handle 30, outside of the machine and the two arms 31 and 32, just under the 20 bottom 5 and in line with the toothed wheel 24. The arm 31 is shorter than the arm 32 and has pivoted at its end 33, a dog 34. This dog 34 extends outwardly, forming an extension of the arm 31, and has the tooth 35 25 for engagement with the teeth 25 of the wheel 24. The dog 34 is held in yielding engagement with the teeth 25 by the spring 36 which bears against the back of the dog. The longer arm 32 extends farther than the 30 arm 31 and has its outer end 36 formed with an inward extension 37 to which is pivoted a dog 38, having a tooth 39 for engagement with the teeth 25 of the wheel 24. A spring 40 has one end secured to the extension 37 35 and the other bearing against the back of the dog 38. The spring 40 may rest against a projection 41 on the inside of the arm 32.

At one end of the machine on top is placed the title of the party ticket to be voted, or if 40 there be several party tickets for each machine, then the name of each party in a line of voting places. Adjacent to each plate is given the title of the office for which that plate and the tubes beneath are designed for 45 voting. The upper face of the plates 20 are divided off into divisions, one for each set of three holes. At the outer edge of each division is given the name of the person for whom that division and the tubes beneath are 50 designed for voting.

When the machine is ready for voting, the parts are as indicated in Fig. 2 or in the 55 position of Fig. 1 marked "Governor" and "Lieutenant Governor." Here the holes in the plate 20 are out of line with the tubes 15, the material of the top 4 forming a bottom for the holes in the plate 20.

This voting machine is designed for preferential voting where the voter casts his ballot, 60 if he desires, for three candidates for an office, indicating the voter's first, second and third choice. The voter having determined for which candidates he will vote, places a ball in the division on which is the name of 65 the candidate who is the voter's first choice,

putting the ball in the hole in the plate 20 which is marked "1." Then he places a ball in the hole marked "2," in another division, and then in a hole marked "3" in still another division. As soon as a ball is placed 70 in a hole, the disk 21 is locked against rotation and prevents a voter from giving more than one choice to the same candidate.

After the balls have been deposited in the machine and the voter retires, the officer pulls 75 out the slide bar 29, rotating the wheel 24 through the dogs 38, and also the crank arm 26. This causes the bottom head 13, the tubes 15 and the top head 9 to be turned and with them the circular plate 20 fastened by 80 the screw 18 to the spindle 8 of the top head 9. This brings the holes of the plate 20 in alinement with the tubes 15 and the balls drop down the tubes. Reverse movement of the slide bar 29 causes the machine to be set 85 for another voter. If desired, a spring 42 may be used to return the slide bar after it has been drawn out. The rotation of the circular plate 20 with the names of the candidates thereon varies the position of these 90 names so that candidates have equal chances of positions on the top of the machine.

Having described my invention, what I claim is:

1. A voting machine provided with revolvable sets of tubes, a head secured to such tubes and having holes alined with the bores of the tubes and a perforated top above the tops of the tubes. 95

2. In a voting machine, the combination 100 of top and bottom revolvable heads, the top head having holes therein, tubes secured to both heads and having their upper ends in the holes of the top head, a plate secured to the top head and having holes alined with the holes in the top head and the top of the machine having holes therein and between the top head and the plate secured thereto. 105

3. In a voting machine, the combination 110 of top and bottom revolvable heads, the top head having holes therein arranged in sets of three, tubes secured to both heads and having their upper ends in the holes of the top head, a plate secured to the top head and having holes alined with the holes in the top head and the top of the machine placed between the top head and the plate and having holes in sets arranged similar to the sets of holes in the top head and plate. 115

4. The combination of a plate, having 120 holes in sets of three with a disk secured in the midst of the set of holes and having a notch.

5. The combination of several sets of revolvable tubes adapted to serve as containers 125 and provided with visual spaces to allow inspection of the contents, and means for revolving the tubes at the same time.

6. The combination, in a voting machine, 130 of a head provided with a set of tubes, a

toothed wheel attached to the head, other heads, each provided with a set of tubes and having attached to the head a crank arm, a rod connecting the crank arms and the toothed wheel, and a slide provided with two dogs adapted to be engaged by springs with the teeth on opposite sides of the toothed wheel, respectively.

In testimony whereof I affix my signature in presence of two witnesses.

KIRBY FITZPATRICK.
